UNITED STATES PATENT OFFICE

146,327

DESIGN FOR A CONTROL KNOB

Bertrand N. Trombley, Birmingham, Mich., assignor to The Murray Corporation of America, Detroit, Mich., a corporation of Delaware

Application December 28, 1945, Serial No. 125,068

Term of patent 3½ years

(Cl. D26—1)

To all whom it may concern:

Be it known that I, Bertrand N. Trombley, a citizen of the United States of America, residing in Birmingham, in the county of Oakland, State of Michigan, have invented a new, original, and ornamental Design for a Control Knob, of which the following is a specification, reference being had to the accompanying drawing, forming a part thereof, wherein:

Figure 1 is a view in elevation of a control knob showing my new design;

Fig. 2 is a plan view of the knob illustrated in Fig. 1;

Fig. 3 is a side view of the knob illustrated in Fig. 1; and

Fig. 4 is a rear view of the knob illustrated in Fig. 1.

I claim:
The ornamental design for a control knob, substantially as shown.

BERTRAND N. TROMBLEY.
